AIR DELIVERY DEVICE

Alfred R. Gilbert, New York, N. Y., assignor to
 Anemostat Corporation of America, New York,
 N. Y., a corporation of Delaware

Application October 7, 1946, Serial No. 701,695

2 Claims. (Cl. 98—40)

1

This invention relates to ventilating apparatus, and has particular reference to improvements in devices for effecting delivery of air into rooms or other enclosures.

More particularly, the invention relates to improvements in air delivery devices of the type comprising a plurality of open-ended members of different sizes disposed in spaced apart relationship to each other within one another to divide air flowing through the device into separate streams.

One special object of the invention is to provide the members of devices of the type mentioned with novel spacing elements so as greatly to facilitate obtaining their proper spaced apart relationship to one another during their assembly.

Another special object of the invention is to provide simple, easily applied means for cooperation with the spacing elements to secure the members firmly and rigidly in assembly with one another.

With the foregoing and other objects in view, which will become more fully apparent as the nature of the invention is better understood, the same consists in an air delivery device embodying the novel features of construction, combination and arrangement of parts as will be herein-after more fully described, illustrated in the accompanying drawings and defined in the appended claims.

In the accompanying drawings, wherein like characters of reference denote corresponding parts in the different views:

Fig. 1 is a central, longitudinal section through an air delivery device constructed in accordance with the invention.

Fig. 2 is a cross section on the line 2—2 of Fig. 1.

Figs. 3, 4 and 5 are views similar to Fig. 1 illustrating alternative forms of the invention; and

Fig. 6 is a horizontal section illustrating a detail of the invention.

Referring to the drawings in detail, it will be observed that the air delivery device chosen for purposes of illustrating the invention is of a well known general type comprising a plurality of open-ended, hollow, flaring members of different sizes disposed in spaced apart relationship to each other within one another to divide air flowing through the device into a plurality of separate, flaring streams and thereby cause it to be diffused and to be delivered from the device substantially draftlessly. It is to be understood, however, that the features comprising the in-

vention are not limited to use with air outlet devices of the particular type illustrated, but may be used with any air outlet device comprising an outer open-ended member and one or more other members disposed therein in spaced relationship thereto.

As illustrated in the drawings, the device is composed of four flaring members; viz., an outermost member 10, an innermost member 11 and two intermediate members 12, 12. It is understood, however, that the number of members comprising the device is arbitrary. It is also to be understood that the members may have either the same or different amounts of flare, or no flare at all, and that they may be of either regular or irregular shape in cross section, depending upon just how it may be desired to have the separate air streams flow through and from the device in particular instances. Further it is to be understood that the members, whether flared or not, may be of circular or any other desired shape in end elevation and that the innermost member 11 may be either solid or hollow and, if hollow may be either closed or open at its rear end as desired. Additionally it is to be understood that the outermost member 10 may be provided at its rear end with a neck 13 to adapt the device for connection with an air supply duct, or may be devoid of such a neck if, for example, a fan or the like is to be employed simply for circulating room air through the device. The air to be delivered from the device is, of course, supplied to the device through the open, rear end of the larger or outermost member 10.

The present invention is particularly concerned, on the one hand, with the provision of simple, practical means to insure proper spacing of the members relative to each other during their assembly, and on the other hand, to the provision of simple, practical means for fastening said members securely together in their assembled relationship to each other, thereby to increase the production rate and, at the same time, to reduce the production cost of the device.

To the end of providing simple means to facilitate proper assembly of the members, said members are provided, at suitable angularly spaced points, with suitable spacing formations 14. The members may be pressed, cast or otherwise formed from metal or they may be molded, pressed or otherwise formed from plastic or other suitable material and in that event the spacing formations 14 may be formed as integral parts of said members; i. e., as bosses. Alternatively, the members may be formed from sheet metal or

other suitable sheet material and in that event the spacing formations 14 may be separate from and may be secured to the members in any suitable manner. In any event, the spacing formations are fixed parts of the members so that by the mere act of assembling the members they serve to space the members proper predetermined distances apart. As shown, said formations may be provided at the inner side of the outermost member 10, at the outer side of the innermost member 11 and at both sides of the intermediate member or members 12, and between each two adjacent members they may be engageable in end to end relationship with each other to accomplish their spacing function. Further to accomplish their spacing function properly, the ends of said spacing formations are inclined forwardly and outwardly and may be either flat, or dovetailed as indicated at 14' in Fig. 6, or otherwise similarly formed, so that they may be seated properly in end to end relationship to each other only when the flaring members are properly spaced apart and are angularly positioned with the said spacing formations in alinement with each other.

If the ends of the spacing formations are flat, it is easy to "feel" when the flaring members are properly positioned relative to each other and, consequently, easy to properly position said members relative to each other during their assembly without any necessity of employing jigs or other special spacing and supporting means for the members as heretofore required and used. If, on the other hand, the ends of said spacing formations are dovetailed or similarly formed to interfit with each other only by longitudinal movement of the members relative to each other and to thereby hold the members against rotation relative to each other, mere mating of the ends of said formations is all that is required to insure proper positioning of the members relative to each other.

The means for fastening the members together may consist as shown in Figs. 1 to 3 of the drawings, simply of headed screws 15 passed from the exterior of the outermost member 10 through alined holes in all except the innermost member 10, and threaded at their inner ends into said innermost member.

Alternatively, screws 16 may be passed from the interior of the innermost member through alined holes in all except the outermost member and may be threaded at their outer ends into said outermost member as shown in Fig. 4 of the drawings. In either case the screws may be straight and rigid or they may be flexible, as indicated at 17 in Fig. 5, if the holes in the respective members should not form a continuously straight passageway.

There may be as many of the screws 15, 16 or 17 as desired and they need not necessarily extend through the spacing formations 14. Preferably, however, they do extend through holes provided in said spacing formations as thereby a particularly firm and rigid assembly of the members is obtained. By the act of properly assembling the members as by "feel" or otherwise, the screw accommodating holes in said members become alined and it is easy to insert the screws in said holes.

Obviously, between any two members of a device of the type under consideration, the spacing formations may in some cases be entirely on one of the members instead of partly on one and partly on the other of the members.

Fig. 3 of the drawings illustrates that the outer of a plurality of members which are assembled as a unit in accordance with the present invention may be provided with lugs or equivalent 5 spacing formations 18 for engagement with companion lugs or equivalent spacing formations 19 on an outermost member 20 to properly space the unit from said outermost member. This figure also illustrates that the unit may be removably fastened to the outermost member 20 by screws 21 extending loosely through the spacing formations 18 and threaded into spacing formations 19.

From the foregoing description considered in connection with the accompanying drawings it is believed that the features comprising the invention will be clearly understood and their advantages appreciated. It is desired to point out, however, that while only a single, specific embodiment of the invention has been illustrated and described, the same is readily capable of various other specifically different embodiments within its spirit and scope as defined in the appended claims.

25 I claim:

1. An air delivery device comprising an outer open-ended hollow member, an inner member disposed within and spaced from said outer member, said members being separate from each other and having formations fixed with respect thereto and extending inwardly and outwardly therefrom, respectively, and disposed in end to end abutting relationship to each other to space said members apart, the abutting ends of said formations being inclined rearwardly and inwardly relative to the longitudinal axis of the device to limit rearward movement of said inner member relative to said outer member, the abutting ends of said formations also interfitting with each other to hold said members against rotation relative to each other about the longitudinal axis of the device.

2. An air delivery device comprising an outer open-ended hollow member, an inner member disposed within and spaced from said outer member, said members being separate from each other and having formations fixed with respect thereto and extending inwardly and outwardly therefrom, respectively, and disposed in end to end abutting relationship to each other to space said members apart, the abutting ends of said formations being inclined rearwardly and inwardly relative to the longitudinal axis of the device to limit rearward movement of said inner member relative to said outer member, the abutting ends of said formations also having interfitting recess and projection formations to hold said members against rotation relative to each other about the longitudinal axis of the device.

60 ALFRED R. GILBERT.
